US00D992687S

(12) **United States Design Patent** (10) **Patent No.:** **US D992,687 S**
(45) **Date of Patent:** **** Jul. 18, 2023**

(54) **FAUCET STREAM STRAIGHTENER**

(71) Applicant: **Neoperl GmbH**, Mullheim (DE)

(72) Inventor: **Marc Tempel**, Freiburg (DE)

(73) Assignee: **Neoperl GmbH**, Müllheim (DE)

(**) Term: **15 Years**

(21) Appl. No.: **29/846,734**

(22) Filed: **Jul. 19, 2022**

Related U.S. Application Data

(62) Division of application No. 29/749,199, filed on Sep. 3, 2020, now Pat. No. Des. 962,385, which is a division of application No. 29/649,938, filed on Jun. 4, 2018, now Pat. No. Des. 898,163, which is a division of application No. 35/502,057, filed on Nov. 23, 2016 (U.S. filing date under 35 U.S.C. 384), and having an international filing date of Nov. 23, 2016, now Pat. No. Des. 822,159.

CLAIM

The ornamental design for a faucet stream straightener, as shown and described.

DESCRIPTION

FIG. 1 is a top view of a faucet stream straightener in accordance with my design;

FIG. 2 is a top perspective view thereof;

FIG. 3 is a bottom plan view thereof;

FIG. 4 is a bottom perspective view thereof;

FIG. 5 is a front elevational view thereof;

FIG. 6 is a right side elevational view thereof;

FIG. 7 is a rear side elevational view thereof; and,

FIG. 8 is a left side elevational view thereof.

The broken lines represent portions of the faucet stream straightener that form no part of the claimed design.

1 Claim, 8 Drawing Sheets
